UNITED STATES PATENT OFFICE.

WILLIAM FULLER HOSFORD, OF OAK PARK, ILLINOIS, ASSIGNOR TO WESTERN ELECTRIC COMPANY, INCORPORATED, A CORPORATION OF NEW YORK.

METHOD OF AND APPARATUS FOR DRYING AND STORING DRIED MATERIAL PREPARATORY TO PROCESSING.

Application filed July 26, 1923. Serial No. 653,845.

This invention relates to a method of and apparatus for drying and storing dried material.

An object of the invention is to remove from material practically all of the moisture contained therein and thereafter to store the dried material in a chamber so supplied with air of low moisture content that the material may be stored for considerable lengths of time without the introduction of moisture therein and operators may work around the stored material without serious discomfort.

Another object is to maintain a core independent of atmospheric humidity conditions during the drying thereof and the application of a sheath thereto.

The method and apparatus constituting the invention is especially adapted for drying telephone cables constituting a plurality of copper conductors, each insulated with paper tapes and stranded into cable form before the application of a lead sheath to the cable. It is to be understood, however, that the improved method and apparatus is not limited to the drying of cable, but may be employed for preparing other materials for other forms of processing and for various other purposes without departing from the spirit and scope of the invention.

It is believed that the improved method will be clearly understood by a description of the apparatus by which it may be performed and the accompanying drawing, Figs. 1 and 2 of which illustrate in diagrammatic form plan and elevation views respectively of apparatus as utilized in the drying of a cable of insulated conductors preparatory to the application of a sheath therearound.

Referring to the drawings, a plurality of treating enclosures 10 are associated through openings in the ends 12 thereof with a common receiving or storage enclosure 13 which is provided with a plurality of openings 22 through which cables may be fed from portable reels 25 in the enclosure 13 to a corresponding number of lead presses 23 of any well-known type for applying a lead sheath to the cables. Each enclosure 10 is provided with doors 14 and 19 adapted to close openings in ends 11 and 12 respectively thereof, the door 19 being adapted to be maintained in a partially closed position when desired. An air conditioning appara-

tus diagrammatically illustrated by the rectangle 15, and which may be of any well-known type equipped with a suitable automatic temperature and humidity regulating means, is connected with the enclosure 13 by means of a pipe 31 for continuously supplying the enclosure 13 with air of low moisture content. Each of the treating enclosures 10 may be selectively heated by steam, or other suitable heating medium, flowing through pipe coils 20 associated therewith. A conduit 17, including a valve 18, also serves to connect each enclosure 10 with a suitable air pump or blower apparatus 16 for withdrawing air from the enclosure. An exhaust apparatus (not shown), but which may be of any suitable type, and a source (also not shown) of air dried by chilling or by chemical treatment, are connected to each enclosure 10 by conduits 21 and 30 respectively. Valves 32 and 33 are included in the conduits 21 and 30 respectively for opening and closing such conduits.

In practicing the method, the cable of paper insulated wire is wound upon a portable reel 25 which serves as a take-up reel for the cable stranding machines. A plurality of reels 25 are introduced into an enclosure 10 through the opening formed in the end 11 thereof by the opening of the door 14, the door 19 at this time completely closing the opening in the end 12 of such enclosure 10. After one of the enclosures 10 has been completely loaded with reels 25 containing the cable to be dried, the door 14 is closed, rendering the enclosure airtight. The door 19 is then partially opened to provide for a circulation of air between the enclosure 13 and the selected enclosure 10. The temperature of the enclosure 10 is then raised to approximately 260° Fah. renheit as soon as may be possible by the flow of steam or other heating medium through the associated coils 20. At the same time air having a moisture content of approximately 10 per cent and heated to a temperature between 100° Fahrenheit and 110° Fahrenheit, obtained from the air conditioning apparatus 15, is introduced into the enclosure 10 through the opening in the end 12 provided by the partially opened door 19. This air is drawn through the enclosure 13 and the enclosure 10 by means of a pump or blower 16 through the pas-

2

sageway 17, the valve 18 being open. Due to the heating of the enclosure 10 by the coils 20, the air circulating therethrough is raised to an average temperature of 220° 5 Fahrenheit with a resulting humidity of one per cent. This air is brought into contact with the cables on the reels 25 within the enclosure 10 and serves to remove a considerable portion of the moisture in the 10 cables and to facilitate the heating of said cables. After the circulation has been maintained for about three hours, it is stopped by closing the valve 18 and the door 19 is then closed so as to render the 15 end 12 of the enclosure 10 air-tight. The absolute pressure in the enclosure 10 is then reduced to that corresponding to one inch of mercury or less by the opening of the valve 32 in the conduit 21, serving to connect the exhaust apparatus with the enclosure 10. The reduced pressure is maintained for a period of from three to twenty-one hours, dependent upon the number of 20 conductors comprising the stranded cable.

25 The combined treatment of the cable by heat and vacuum just described withdraws from the cables on the reels 25 substantially all moisture remaining after the first-mentioned period of treatment. Atmospheric pressure 30 is then restored in the enclosure 10 by opening the valve 33 in the conduit 30, thereby admitting air which has been previously dried by chilling or by being chemically treated.

35 The door 19 is then completely opened and the reels 25 containing the treated cables are withdrawn from the enclosure 10 into the enclosure 13 by operators working within the enclosures. As the various lead 40 presses 23 are in position to receive cables, the cable reels may then be properly positioned before the openings 22 in the enclosure 13 so that the cables may be withdrawn therefrom and passed through the corresponding lead presses 23 which apply lead 45 sheaths thereto. The door 19 is then again completely closed. The valves 32 and 33 are also closed and upon the subsequent opening of the door 14, the particular enclosure 10 which has been emptied is ready 50 to be loaded with a new charge of reels of cable, the cycle of operations previously described being repeated during the time the previously treated cables are being sheathed by the presses 23. Each of the 55 enclosures 10 may be operated in the manner described, and upon the completion of the treating of the cables, the reels may be moved therefrom into the common storage chamber 13. It will be noted that at no 60 time are the doors 14 and 19 of a particular enclosure 10 contemporaneously in an opened or partially closed position.

Although the air within the enclosure 13 is maintained at a temperature ranging be-

tween 100° Fahrenheit and 110° Fahrenheit, this temperature does not cause serious discomfort to the operators working within the enclosure for the reason that the moisture content of such air is as low as ten 70 per cent.

The relation of the size of the enclosure 13 to the amount of air received from the conditioning apparatus 15 and the weight of the cables on the reels 25 is such that when 75 an enclosure 10 is opened and the heated cables on the reels 25 discharged therefrom into the enclosure 13, the temperature in the latter enclosure will not be raised above the predetermined limit of 110° Fahrenheit. 80 Furthermore, the storage enclosure, being directly connected with the treating enclosures and being constantly supplied with dry air, it is evident that not only are the cables maintained independent of outside 85 atmospheric humidity conditions throughout the drying process and the storage period, but also the cables may be stored therein for a considerable length of time without introducing any moisture therein. 90

Although, as shown, a plurality of treating enclosures 10 may be used with a single storage enclosure 13 and a plurality of lead presses 23 may be supplied from a single enclosure 13 and the associated enclosures 95 10, it is evident that this method is not limited to this particular arrangement, since the enclosures 10 and 13 may be individually associated and a single lead press employed for such a combination of enclosures. 100

What is claimed is:

1. The method of preparing material for processing, consisting in drying the material in one enclosure, transferring the dried material to a storage enclosure, and maintaining the material independent of atmospheric humidity conditions continuously throughout the drying, transferring and storage thereof. 105

2. The method of preparing material for processing, consisting in removing the moisture therefrom in a plurality of stages in one enclosure, and transferring the dried material under substantially the same humidity conditions to a storage inclosure containing air of low moisture content. 110 115

3. The method of preparing material for processing, consisting in removing the moisture therefrom in a plurality of stages in one enclosure, transferring the dried material to a storage enclosure containing air of low moisture content, and maintaining the material independent of atmospheric humidity conditions continuously during the drying, transferring and storage thereof. 120 125

4. The method of preparing material for processing, consisting in removing moisture therefrom in one inclosure and thereafter transferring the material under substantially the same humidity conditions to a storage 130

enclosure containing air of a predetermined moisture content.

5. The method of preparing material for processing, consisting in depositing the material in an enclosure, producing a vacuum in the enclosure to remove moisture from the material, re-establishing atmospheric pressure conditions in the enclosure, and transferring the dried material in the presence of air of predetermined moisture content to a storage enclosure.

6. The method of preparing material for processing, consisting in depositing the material in an enclosure, heating the enclosure to a relatively high temperature to remove moisture from the material, producing a vacuum in the enclosure to remove substantially all remaining moisture from the material, re-establishing atmospheric pressure conditions in the enclosure, and transferring the dried material under substantially the same humidity conditions to a storage enclosure containing air of predetermined moisture content at a relatively low temperature.

7. The method of preparing material for processing, consisting in depositing the material in an enclosure, heating the air in the enclosure to a relatively high temperature, producing a vacuum in the enclosure, introducing previously dried air into the enclosure to re-establish atmospheric pressure therein, and thereafter transferring the dried material under substantially the same humidity conditions to a storage enclosure supplied with air of low moisture content.

8. The method of drying cable preparatory to applying a sheath thereto, consisting in heating the air surrounding the cable to a relatively high temperature, thereby removing a portion of the moisture from the cable, producing a vacuum around the cable to remove substantially all of the remaining moisture therefrom, transferring the cable in the presence of air of low moisture content to a storage enclosure, and maintaining the cable independent of atmospheric humidity conditions during the removal of the moisture therefrom, the storage and transfer thereof, and the application of the sheath thereto.

9. The method of drying cable preparatory to applying a sheath thereto, consisting in depositing the cable in an enclosure, heating the air in the enclosure to an average temperature of 220° F. to reduce the moisture content of the air to one per cent, reducing the pressure within the enclosure to correspond with one inch of mercury, maintaining the reduced pressure for at least three hours contemporaneously therein, maintaining the temperature of the enclosure at approximately 260° F., then introducing into the enclosure previously dried air to re-establish atmospheric pressure, and thereafter transferring the cable under substantially the same humidity conditions to a storage enclosure containing air having a moisture content of approximately ten per cent.

10. In an apparatus for drying material, two enclosures, one of said enclosures designed so that it may be closed air-tight, means for establishing communication between the enclosures, means for heating the air in the first-mentioned enclosure, means for creating a vacuum in said first-mentioned enclosure after it is closed air-tight, and means for supplying the other enclosure with air of predetermined moisture content.

11. In an apparatus for drying material, a storage enclosure, a treating enclosure adapted to be made air-tight and directly connected with the storage enclosure, a door for separating the enclosures, and means for supplying air of predetermined moisture content to the storage enclosure.

12. A method of treating materials preparatory to processing, which consists in subjecting the materials to a heating medium in one enclosure, simultaneously therewith exposing said materials to air of a predetermined moisture content, transferring the materials to a separate storage enclosure, and maintaining the materials independent of atmospheric humidity conditions continuously throughout the treating, transferring and storing thereof.

In witness whereof, I hereunto subscribe my name this 14th day of July A. D., 1923.

WILLIAM FULLER HOSFORD.
